UNITED STATES PATENT OFFICE

2,566,799

ROTARY SEALER

James M. Humphrey, New Richmond, Wis.

Application November 7, 1946, Serial No. 708,248

8 Claims. (Cl. 154—42)

1

This invention relates to improvements in devices for sealing the open ends of bags, particularly bags formed of sealable material such as cellophane, or other heat softenable or heat moldable material, and is especially directed to improved means for feeding the bags into and away from the bag sealing device.

The sealing device itself may be such as is particularly illustrated and described in my prior application Serial Number 643,631, filed June 26, 1946, for "Rotary Type Heat Sealer," now abandoned, to which reference may be had for a detailed description of the sealer mechanism.

Since this type of sealer has been in use many attempts have been made to provide automatic feeding means to carry the filled bags to be sealed to and away from the sealing rollers.

These various attempts have failed to provide a satisfactory mechanism, the chief difficulty having been encountered in feeding the bag ends into the sealing rollers. In the prior device the bag ends have been brought to the vicinity of the location at which the rollers most nearly contact each other and the gripping action of the rollers has then been depended upon to carry the bag ends between them. This has resulted in imperfect closing and sealing of the bags since the bag ends are frequently presented to the sealing rollers in a crumpled or creased condition, or at an angle to the plane of rotation of the rollers or not at the proper height for perfect sealing. There is also a tendency in the previously used feeding devices for the bag ends to slip or turn as they are passing through the rollers and for an occasional bag to adhere to one of the rollers and be carried by the roller away from the feeding mechanism.

It has also been found difficult to maintain the moving parts of the feeding mechanism in exact synchronism with the turning of the sealing rollers.

At the same time it is highly desirable to provide a substantially automatic feeding device for such a sealer to increase its efficiency and speed of operation, reduce the necessary amount of manual labor and provide more perfect seals.

It is therefore among the objects of the present invention to provide an improved rotary type bag sealer having bag feeding mechanism which will firmly grip the bags at a location convenient to the operator of the sealer and hold the bags in firmly gripped condition until they have passed between the sealing rollers and will support the bags on movable conveyor means as they approach and leave the sealing rollers.

2

A further object resides in the provision of improved feeding means for a rotary type bag sealer which is fully adjustable to maintain the proper pressure on the bags as they are fed between the sealing rollers.

A still further object resides in the provision of improved feeding means for a rotary type bag sealer in which the movable portions of the feeding means are operatively connected with the sealing rollers in a manner such that the feeding means is driven in exact synchronism with the sealing rollers.

Another object resides in the provision of improved feeding means for a rotary type bag sealer which feeding means is simple and economical to manufacture and install and durable in operation.

Other objects and advantages will become apparent from a consideration of the following description in conjunction with the accompanying drawings in which:

Fig. 1 is a perspective view of a rotary type bag sealer showing automatic feeding means illustrative of the invention applied thereto;

Fig. 2, a perspective view of the lower portion of the sealing machine and the automatic feeding means with the covers removed from the automatic feeding means to show the construction thereof;

Fig. 3, a side elevational view of a complete bag sealing unit including a supporting table with a conveyor belt thereon, a rotary type sealing machine mounted above the table and an automatic feeding device for the sealing machine;

Fig. 4, a top plan view of a fragmentary portion of the table shown in Fig. 3, parts being broken away to better illustrate the construction thereof;

Fig. 5, a bottom plan view on an enlarged scale of the automatic feeding device for the rotary sealer;

Fig. 6, a transverse sectional view on the line 6—6 of Fig. 5;

Fig. 7, a transverse sectional view on the line 7—7 of Fig. 5;

Fig. 8, a sectional view on an enlarged scale of a modified sealing roller adapted for the application of the automatic feeding means thereto;

Fig. 9, a view similar to Fig. 8 showing a further modified form of sealing roller; and

Fig. 10, an elevational view on an enlarged scale showing a fragmentary portion of one of the feeding chains of the automatic feeding mechanism.

With continued reference to the drawings, the

heat sealing machine comprises, in general, a tubular vertical column 10 having a flange 11 at its lower end by means of which the standard or column 10 may be rigidly secured to the top of a suitable support, such as the table, generally indicated at 12. A tubular sleeve 13 is vertically slideable on the standard 10 and has secured thereto a gear casing 14 from the bottom of which depend two vertical shafts 15 and 16 on the lower end of which the sealing rollers 17 and 18 are respectively secured, these rollers being enclosed in the guard shield or cover 19 shown in Fig. 1 but being illustrated in bottom plan view in Fig. 5.

Below the gear casing 14 and immediately above the heat sealing rollers 17 and 18, a bearing bracket 20 extends outwardly from the sleeve 13 and the roller shafts 15 and 16 pass through this bracket and are journaled therein, suitable means being associated with the bracket to vary the pressure exerted between the two rollers. Between the bearing bracket 20 and the gear casing 14 a switch bracket 21 is secured to the sleeve 13 and extends outwardly to locate the operating switches for the machine at a position convenient to the operator. One of these switches, for example the switch 22, may be connected to control the drive motor of the sealing machine. Another switch, such as 23, may be connected to control the heating of the sealing rollers and a third switch 24 may be connected to control the heating of the preheating elements 25 and 26 through which the bags pass before passing between the sealing rollers. The preheating means and the roller heating means are sufficient to soften the material of the bags to an extent such that when the sides of the open end portions of the bags are pressed together by the sealing rollers, these sides will permanently adhere to each other providing a substantially airtight seal for the bag. The bags are ordinarily made of cellophane or some similar heat softenable material.

Above the gear casing 14 a motor bracket 21 is secured to sleeve 13 by an adjustable connection which includes the set screw 28. A drive motor 29 is mounted on the upper surface of bracket 21 and connected by a suitable drive belt 30 with a drive shaft extending from the gear casing 14.

The distance between the sealing rollers and the top surface of the table or support 12 is controlled by adjusting means including the cable 31 which passes over a sheave 32 at the upper end of column 10 and is wound on a winch or windlass 33 having a manually operable crank 34 for raising and lowering the sleeve 13 and the mechanism carried thereby, on the standard 10. By this arrangement the sealing machine may be adjusted to seal bags of different heights.

An automatic bag feeding device, generally indicated at 35, is attached to the lower portion of the bag sealing machine and operatively associated with the sealing rollers. This feeding device is operative to grasp the upper ends of bags, as indicated at 36, moved along a conveyor belt 37 carried by the table 12 and to carry said bags through the sealing machine in a position such that the bags will be uniformly sealed over a sufficient area to provide a substantially air-tight and moistureproof seal for each bag.

The support or table 12, as is particularly illustrated in Figs. 1 and 3, has an upper surface portion 38 upon which the machine standard 10 is secured and which extends from each of two

opposite sides of the standard location. Along one edge thereof the table is provided with a longitudinal depression 39, the outer side of which is constituted by a cover plate 40 of sheet metal or some similar relatively thin material. The conveyor belt 37 runs in the depression 39 and is driven by suitable mechanism, including the drive motor 41, the reduction gear unit 42, the belt pulley 43, and the V-belts 44 and 45. The motor and reduction gear unit may be conveniently supported on a table shelf 46 disposed between the center legs 47 and one set of end legs 48 and reinforced by suitable braces 49 and 50. A set of end legs 51 supports the end of the table opposite the end supported by the legs 48.

With this arrangement bags, as indicated at 36 in Fig. 3, may be placed upon the conveyor belt 37 at one end of the table 12 and the conveyor belt 20 will carry the bags to the receiving end of the automatic feeding mechanism 35, which mechanism will carry the bags through the sealing machine. As the bags pass through the sealing machine, they are continuously supported on the conveyor belt 37, and as they leave the machine the belt carries the sealed bags away from the machine as indicated at 36' in Fig. 3. The speed of the conveyor belt 37 is synchronized with the speed of the automatic feed device 35 so that the bags will not be tilted or upset as they pass through the feed mechanism and the sealing machine but will retain a substantially vertical position on the conveyor belt and will be sealed over substantially uniform areas by the sealing machine.

This combination of supporting table, conveyor belt, and drive means therefor, automatic feeding device and rotary sealing machine, provides a substantially automatic bag sealing apparatus, the use of which requires only the placing of the bags on the conveyor belt at one end of the table and the removal of the sealed bags from the conveyor belt at the discharge end of the table.

The improved automatic feeding mechanism 45 is particularly illustrated in Figs. 2 and 5 to 10, inclusive. This mechanism comprises a pair of flat arms 52 and 53 secured to the under side of the bearing bracket 20. In order to position these arms at the level of the lower ends of the corresponding sealing rollers 17 and 18, each arm is provided with a substantially Z-shaped end portion, as indicated at 54 for the arm 52 and at 55 for the arm 53. As is particularly illustrated in Fig. 2 in connection with the arm 53, the upper 55 substantially horizontal part of the Z-shaped end portion 55 is secured to the under surface of bearing bracket 20 by suitable means, such as the bolt 56. The substantially vertical part of the Z-shaped end portion extends downwardly from the end of the horizontal portion past the sealing roller 17 to the level of the bottom end of the sealing roller and from the bottom end of the vertical part a substantially horizontal arm portion 57 extends away from the roller. The lower horizontal parts of the arms 52 and 53 have substantially parallel edges adjacent the respective Z-shaped end portions but have inwardly tapered outer edge portions at their outer ends, as is clearly illustrated in Fig. 5. The inner edge portions of the two arms are straight, parallel and opposed but spaced apart as is also clearly shown in Fig. 5. At its outer end the arm 52 carries a chain sprocket 58 journaled on an axle 59, the lower end of which is fixed in the outer end portion of the arm and the arm 53 carries a similar

chain sprocket 60 journalled on an axle 61 carried by the arm. The two sprockets 58 and 60 are disposed in the same substantially horizontal plane and rotate in close proximity to each other but without interference between them.

Each of the sealing rollers 17 and 18 is made somewhat longer in its vertical dimension than the corresponding rollers shown in application Ser. No. 643,631 referred to above, and each roller has a chain sprocket on the bottom end thereof. In the arrangement shown in Fig. 8 wherein the construction of the roller 18 is shown in detail, the two rollers being of the same construction, roller 18 is provided with an annular recess 62 located between an apertured central boss 63 which receives the lower end of drive shaft 16, and a concentric peripheral rim 64, the outer surface of which is preferably grooved, knurled, or otherwise treated to provide a roughened surfaced, as indicated at C5. Roller heating elements 66 are disposed in the recess 62 and below these heating elements the bottom wall 67 connects the central boss with the rim 64. This wall 67 is made sufficiently thick so that chain sprocket teeth 68 may be provided thereon. These teeth may be conveniently provided integrally with the roller by cutting a groove 69 in the cylindrical surface of the roller adjacent the bottom end thereof to provide a ridge or bead 70 and then machining the ridge or bead 70 to provide the separate sprocket teeth 68. The effective diameter of the sprocket having the teeth 68 is such that the speed of a feed chain driven by said sprocket is exactly the same as the peripheral speed of the corresponding roller.

In the modified arrangement shown in Fig. 9 the roller 18 is of the same size and construction as the sealing rollers shown in my prior application referred to above, and a sprocket member 71 is formed from a flat metal plate having sprocket teeth 68' cut into the periphery thereof. This plate may be attached to the bottom end of the roller by suitable means such as screws 12 extending through the plate and into the bottom wall 67 of the roller.

While the roller-carried chain sprocket may be provided by either of the above-described methods, it has been found that certain factors favor the provision of the chain sprocket integral with the roller, as illustrated in Fig. 8, as this method provides a sprocket which is truly concentric with the roller and cannot become loosened or slip relative to the roller, has the same heat expansion and contraction characteristics as the remainder of the roller, and substantially the same wearing characteristics.

For the sake of simplifying the description the sprocket for the roller 17 has been indicated by the numeral 72 in Fig. 5 and the similar sprocket for the roller 18 has been designated by the numeral 73, these references being applied without regard to the manner in which the sprocket is provided.

An endless flexible member, such as the chain generally indicated at 74, surrounds the sprocket 72 on roller 17 and the sprocket 58 at the outer end of arm 52 which extends outwardly from the roller 17. A similar member, generally indicated at 75, surrounds the sprocket 73 on roller 18 and the sprocket 60 at the outer end of arm 53 which extends outwardly from roller 18. Between the sprocket 72 and the sprocket 58 a guide sprocket 76 is journalled on an extension 77 of arm 52 to guide the outer flight of chain 74. Between this guide sprocket and sprocket 72 an idler

sprocket 78, journalled on the outer end of an arm 79, the inner end of which is pivotally mounted on the arm 52 by a pin 80, bears on the outer side of the outer flight of chain 74 and is resiliently urged into chain-tightening contact with the outer flight of the chain by a coiled tension spring 81, one end of which is secured to the outer end of arm 79, the opposite end of which is secured to arm 52 adjacent the roller 17. A guide sprocket 82 mounted on extension 83 of arm 53 guides the outer flight of chain 75 and idler sprocket 84 journalled on the outer end of arm 85, the inner end of which is pivotally mounted on arm 53 by pin 86, is held in chain-tightening contact with the outer flight of chain 75 between sprockets 82 and 73 by coiled tension spring 87, one end of which is secured to the outer end of arm 85, and the opposite end of which is secured to arm 53 adjacent roller 18.

As is clearly illustrated in Fig. 5, the inner flights 88 and 89 of chains 74 and 75, respectively, are parallel and opposed between the inner edges of the supporting arms 52 and 53. These inner flights of the chains are resiliently urged into contact with each other by spring pressed chain guide members 90 and 91.

As clearly shown in Fig. 6, the chain guide member 91 comprises a flat plate rigidly secured to arm 53 by suitable means, such as bolts one of which is indicated at 92. This plate overlaps the upper surface of arm 53 and has its edge which extends beyond the inner edge of arm 53 in contact with the outer side of the inner flight 89 of chain 75. The guide 90 also comprises a flat plate which overlaps the upper surface of arm 52 and has its edge positioned beyond the inner edge of arm 52 in contact with the side of the inner flight 88 of chain 74. The guide 90 is held in contact with the arm 52 by suitable means, such as pins 93 and 94 extending through the arm and through respective slots in the guide 90 and provided with heads overlying the upper surface of the guide adjacent the slots. This construction permits the guide 90 to slide on the upper surface of the arm 52 a small amount toward and away from the opposed edge of guide 91. Near its outer end the guide 90 is provided with an upstanding portion 95 at its outer edge, this portion 95 being provided with an extension 96 which receives a corresponding end of a coiled compression spring 97, the opposite end of which bears against the inner surface of a bracket 98, of angular shape, which extends across the outer ends of arms 52 and 53 to support the feeder cover, one-half portion of which is shown in Fig. 6 and indicated at 99. A screw 100 threaded through the bracket 98 enters the end of spring 97 to hold the spring in proper operative position. This spring resiliently urges the outer end of spring guide member 90 against the inner flight 88 of chain 74 to force this chain inner flight against the inner flight 89 of chain 75 with a predetermined resilient pressure. At its end adjacent the roller 17 the guide member 90 is urged inwardly by a coiled compression spring 101 which is disposed in a tubular retainer 102 welded or otherwise secured to the arm 53 between the roller 17 and adjacent surface of the vertical part of the Z-shaped arm portion 55. One end of the spring 101 bears against an upstanding lug 103 provided on the guide 90 at its outer edge and the opposite end of the spring bears against a screw plug 104 threaded into the outer end of the spring retainer 102. The pressure of the spring 101 on the guide 90 may be

adjusted by turning the plug in or out of the spring retainer.

The two chains 52 and 53 may be conventional sprocket chains, as is particularly illustrated in Fig. 10. Such chains comprise solid connectors, as indicated at 105, and parallel side plates, as indicated at 106, the connectors and side plates being pivotally united by pins 107 extending through apertures in the end portions of the side plates and solid connectors. In order to particularly adapt this type of chain to the feeding operation described above, the side plates 106 are ground off flat around one side, as indicated at 108 in Fig. 10, so that the chains present flat opposed surfaces between the inner flights thereof, which surfaces will grip and firmly hold the upper ends of the bags without puncturing or tearing the material of which the bags are formed.

The arms 52 and 53 are so arranged that the inner flights of the chains extend along the conveyor belt 37 toward the feed end of the table so that the chains will receive the bags moved toward the sprockets 58 and 60 by the conveyor belt and carry the bags from this point entirely through the bag sealing machine and discharge the sealed bags at the discharge side of the machine onto the conveyor belt from which they may be conveniently removed.

The preheating elements 25 and 26 are supported on the corresponding arms 52 and 53 by suitable angle brackets, as indicated at 109 and 110, and the feed cover parts 99 and 111 are supported at their outer ends on the bracket 98 and at their inner ends on the Z-shaped end portions of the arms 52 and 53. A retaining plate 112 secured to bracket 98 and overlying the cover parts secures the cover parts to this bracket and a somewhat similar plate 113 secured to the Z-shaped end portions of the arms and overlying the parts of the cover secures the cover parts to the Z-shaped end portions of the chain supporting arms. Between the cover portions 99 and 111 a removable cover portion 114 covers the manual adjusting device 115 which controls the rheostat 116 of the preheating elements 25 and 26.

Additional outer end chain guards 117 and 118 are secured to the outer end portions of the arms 52 and 53 by suitable fastening means such as the bolts 119 and enclose the outer sprockets 58 and 60 and the outer portions of the chains to maintain these parts free of dirt and debris and avoid danger of injury to the operator.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. In combination with a bag sealing machine having a pair of opposed sealing rollers and means for driving said rollers; automatic bag feeding means for said machine comprising a pair of arms mounted on said machine and extending outwardly therefrom at the level of said rollers; a sprocket on the outer end of each arm; a sprocket on the lower portion of each roller; a pair of endless chains each surrounding one roller sprocket and the sprocket at the outer end of the corresponding arm, the inner flights of said chains being parallel and opposed and driven at the same speed toward said rollers by said roller sprockets; and means carried by said arms guiding the inner flights of said chains and maintaining an adjusted pressure between said inner chain flights.

2. In combination with a bag sealing machine having a pair of opposed sealing rollers and means for driving said rollers; automatic bag feeding means for said machine comprising a pair of arms mounted on said machine and extending outwardly therefrom at the level of said rollers; a sprocket on the outer end of each arm; a sprocket on the lower portion of each roller; a pair of endless chains each surrounding one roller sprocket and the sprocket at the outer end of the corresponding arm, the inner flights of said chains being parallel and opposed and driven at the same speed toward said rollers by said roller sprockets; means carried by said arms guiding the inner flights of said chains and maintaining an adjusted pressure between said inner chain flights; and spring loaded chain tightening means carried by said arms and operatively engaged with said chains.

3. In combination with a bag sealing machine having a pair of opposed sealing rollers and means for driving said rollers; automatic bag feeding means for said machine comprising a pair of arms mounted on said machine and extending outwardly therefrom at the level of said rollers; a sprocket on the outer end of each arm; a sprocket on the lower portion of each roller; a pair of endless chains each surrounding one roller sprocket and the sprocket at the outer end of the corresponding arm, the inner flights of said chains being parallel and opposed and driven at the same speed toward said rollers by said roller sprockets; means carried by said arms guiding the inner flights of said chains and maintaining an adjusted pressure between said inner chain flights; and spring loaded chain tightening means carried by said arms and operatively engaged with said chains.

4. The combination as defined in claim 1 wherein each of said endless chains is provided with a flattened outer side to grip the material of bags to be sealed without puncturing or otherwise injuring the material.

5. The combination as defined in claim 1 wherein the sprocket on the lower end of each sealing roller is integral with the corresponding roller.

6. The combination as defined in claim 1 wherein said chain guide means comprise a pair of flanged members secured one to each arm along the inner flight of the corresponding chain, and adjustable spring means operatively connected between one of said members and the corresponding arm to adjust the pressure exerted between the inner flights of said chains.

7. The combination as defined in claim 2 wherein the tightening means for each chain comprises an arm pivotally secured at its inner end to the corresponding chain carrying arm; an idler sprocket journaled on the outer end of said pivoted arm and engaging the outer flight of the corresponding chain; and a spring acting between the outer end of said pivoted arm and said corresponding chain carrying arm.

8. Bag sealing apparatus comprising an elongated table having a lengthwise depression along one side thereof; a rotary bag sealing machine mounted on said table above said depression and having a pair of opposed bag sealing rollers; a conveyor belt in said table depression; a pair of arms each supported at one end on said ma-

chine and extending to one side of said machine along said table depression; a chain sprocket at the outer end of each arm; a chain sprocket on the lower end of each sealing roller; a pair of endless chains each surrounding one roller sprocket and the sprocket at the outer end of the corresponding arm, the inner flights of said chains being parallel adjacent and opposed to grip the upper end of bags carried along said conveyor belt and feed them between said sealing rollers; and means driving said conveyor belt at a speed in synchronism with the speed of said bag feeding chains.
